Patented Sept. 16, 1913.

UNITED STATES PATENT OFFICE.

GEORGE HILPERT, OF MORGANTOWN, WEST VIRGINIA.

SASH-LOCK.

1,073,486.

Specification of Letters Patent. Patented Sept. 16, 1913.

Application filed January 21, 1913. Serial No. 743,375.

To all whom it may concern:

Be it known that I, GEORGE HILPERT, a citizen of the United States, residing at Morgantown, in the county of Monongalia 5 and State of West Virginia, have invented new and useful Improvements in Sash-Locks, of which the following is a specification.

This invention relates to sash fasteners; 10 and it has for its object the provision of a swinging leaf mounted on the sash and having a free end associated with a sash and adjacent portion of the frame so as to permit the leaf to be conveniently manipulated 15 and further the provision of spaced devices carried by the frame and adapted for interchangeable engagement with said leaf so as to coöperate therewith to hold the sash against sliding movement in either direction, 20 and means forming a part of the leaf whereby the latter will be positively held against being accidentally moved to a released position.

Another object of the invention is the 25 provision of a fastener which will be constructed with a view of facilitating the operation of locking the sash in any desired adjustment in the frame.

With these and other objects in view, the 30 invention consists of certain novel features of construction, combination and arrangement of parts, as will be hereinafter described and claimed.

In the accompanying drawings:—Figure 35 1 is a front view of a window frame, showing the application of the fastener thereto and indicating the position of the movable element of the fastener relatively of the fixed element of the frame, so as to effect 40 a locked condition of the sash; Fig. 2 is a horizontal section, taken on the line 2—2 of Fig. 1; Fig. 3 is a similar view, showing the movable locking element of the fastener adjusted to a released position; Fig. 4 is a 45 vertical section, taken on the line 4—4 of Fig. 1; and Fig. 5 is a view similar to Fig. 2, showing the movable element adjusted relatively of the fixed coöperating locking element whereby said fixed element forms an 50 abutment or stop to the movable element to prevent the latter from being accidentally released.

The sash guiding strip 1 on the left stile of the window frame herein illustrated is 55 provided at desired intervals with horizontally extending pins 2, which terminate in

outer substantially circular and slightly yieldable heads 3. The lower sash 4 has its left vertical bar provided at a point adjacent to the lower corner of the sash with a hinge 60 plate 5 having alined horizontal knuckles 6, which are associated with similar knuckles 7 and connected therewith by a hinge pin 8. The knuckles 7 are formed upon one of the vertical edges of a movable locking element 65 or leaf 9 which includes a main body portion 10 having a circular opening 11 therein for the interchangeable reception of the pins 2 according to the adjustment of the sash desired. The opening 11 is eccentrically disposed with relation to the head 3 of the pin 2 whereby a portion of the head will extend laterally beyond the adjacent body portion 10 of the leaf 9 to thereby hold the latter against being accidentally drawn over the 70 head 3 when the sash is vibrated laterally in the frame. The body portion 10 of the leaf is gradually reduced toward its manipulating end 12 and provided with a longitudinally curved finger piece 13, which is 75 adapted to engage against the lower horizontal bar of the sash whereby to hold the leaf spaced from said bar when the leaf is adjusted to an inoperative position. This is desirable in that the operation of adjusting 80 the leaf 9 to an operative position is greatly facilitated, it being understood that the fingers of the hand may be conveniently inserted between the portion 12 of the leaf and the lower horizontal bar of the sash so 85 as to operatively present the portion 13 for engagement with the fingers.

It is stated that the strip 1 lies in mutual contact with the body portion 10 of the leaf 9 when the latter is associated with one of 90 the pins 2. In this manner, the portion 13 of said leaf will be spaced from the adjacent vertical stile of the window frame to thereby permit said leaf to be effectually 95 grasped by the hand and the required pressure applied thereto to effect its release from the resilient head 3 of said pin.

The head 3 of each pin is beveled in the direction of the shank of the pin, so that the inner surfaces of the head serve as deflecting and guiding surfaces which tend to hold the main body portion of the leaf 9 100 properly seated behind the head.

Having thus described my invention, what I claim is:—

110 A sash fastener comprising a leaf secured to the sash, a leaf hinged to the first leaf

22
and including a main body portion reduced in width toward its free end and provided with a curved manipulating terminal engaging against the sash whereby to hold the 5 hinged leaf spaced from the sash when said leaf is in an inoperative position, the said hinged leaf having a circular passage therein, and a series of fixed pins carried by the window frame and operable for interchangeable projection into said passage so as to 10

hold the hinged leaf against swinging movement beyond a limited distance and to also hold the sash against any sliding movement.

In testimony whereof I affix my signature in presence of two witnesses.

GEORGE HILPERT.

Witnesses:

WM. H. BAKER,
GUY C. ROSS.
